UNITED STATES PATENT OFFICE

CLARENCE E. SMITH, OF ROCKFORD, ILLINOIS, ASSIGNOR TO HOWARD D. COLMAN, OF
ROCKFORD, ILLINOIS

DESIGN FOR A PORTABLE ELECTRIC FAN

Application filed March 28, 1931. Serial No. 39,282. Term of patent 7 years.

To all whom it may concern:

Be it known that I, CLARENCE E. SMITH, a citizen of the United States, residing at Rockford, in the county of Winnebago and State of Illinois, have invented a new, original, and ornamental Design for a Portable Electric Fan, of which the following is a specification, reference being had to the accompanying drawings, forming part hereof.

Figure 1 is a perspective view of the fan casing and its supporting base as viewed from

a forward position, the fan wheel and guard being omitted.

Fig. 2 is a similar view but looking from the rear.

Fig. 3 is a plan view with the fan wheel and guard shown in broken lines.

I claim:

The ornamental design for a portable electric fan, substantially as shown.

CLARENCE E. SMITH.
